UNITED STATES PATENT OFFICE.

EDWARD J. STALDER AND EDWARD SCHOLZ, OF CHICAGO, ILLINOIS.

GASOLINE RESERVE VALVE.

Application filed August 5, 1921. Serial No. 480,162.

To all whom it may concern:

Be it known that we, EDWARD J. STALDER and EDWARD SCHOLZ, citizens of the United States, residing in Chicago, in the county of Cook and State of Illinois, have jointly invented certain new and useful Improvements in Gasoline Reserve Valves, of which the following is a description.

Our invention relates to improvements in gasoline reserve valves, and more particularly to a valve used in connection with either gravity feed or vacuum feed systems, whereby the flow of gasoline between the supply tank and the carburetor is shut off when the gasoline has reached a predetermined level in the tank, there remaining a reserve quantity of gasoline in the tank, said valve having means whereby the flow may be continued to thence use up the reserve supply. When the supply has been cut off, it indicates to the operator that only the reserve supply of gasoline remains, whereupon the valve may be actuated so as to make use of it to enable him to reach a point where he can receive a fresh supply.

The invention has among its objects the production of a device of the kind described which is simple, convenient, compact, durable, reliable, efficient and satisfactory for use wherever found applicable.

To this end our invention consists in the novel construction, arrangement and combination of parts herein shown and described, and more particularly pointed out in the claim.

In the drawings, wherein like reference characters indicate like or corresponding parts,

Fig. 1 is a side elevation showing our device as applied to a gravity feed system;

Fig. 2 shows our device as applied to a vacuum feed system;

Fig. 3 is a sectional view taken substantially on the line 3-3 of Fig. 4;

Fig. 4 is a sectional view taken substantially on the line 4-4 of Fig. 3;

Fig. 5 is a sectional view taken substantially on the line 5-5 of Fig. 3;

Fig. 6 is a sectional view taken substantially on the line 6-6 of Fig. 3;

Fig. 7 is a view in elevation of a portion of the opposite side of the casing.

In the drawings, wherein we have illustrated the preferred embodiment of our invention, 1 indicates the fuel supply tank,

said tank being of any desired shape and material and located as desired. The fuel 3 in said tank is fed to the carburetor (not shown) through the valve 5, said tank having an outlet 2 formed therein at the bottom thereof, and preferably threaded, as shown, to receive the threaded end 6 of the valve body. A pair of parallel ducts or bores 7 and 8 are formed in the valve body and extend from one end to the other thereof, there being a tapered transverse bore 9 communicating with said parallel bores 7 and 8.

Into said tapered aperture 9 is adapted to be positioned a rotatable plug or core 10, tapered in cross-section and having a pair of apertures 11 and 12 therethrough, said apertures being spaced apart a distance equal to the spacing between the bores 7 and 8 of the valve body so as to be adapted to alternately register with said bores 7 and 8 when said plug is positioned within said opening 9.

As shown, the bores 11 and 12 are arranged mutually transversely of each other so that when one of said bores is in alignment with the axis of the bores 7 and 8, the fluid from the tank may flow therethrough, while at the same time the communication through the other bore will be cut off or interrupted. In the position shown in Figs. 3 and 4, communication is free through the bore 8. One end of the plug 10 is reduced in diameter and preferably formed non-circular in cross-section as at 13, so as to non-rotatably receive an operating handle 16 bearing against the reduced shoulder 15 of the plug, and whereby said plug may be partially rotated to throw one or the other of the bores 11 and 12 into alignment with either of the bores 7 and 8 respectively. A screw 17, or other suitable fastening means, is removably secured into the plug 10, so as to hold it in its seat against the tapered opening 9 and to keep the handle in position, there being a spring washer 18, or other suitable means, to take up play between the head of the screw and operating handle 16. The handle 16 has at its pivotal end an offset portion 19 adapted to slide on an arcuate guideway or bearing 22 formed on one face of the casing body, there being abutments 20 and 21 at the ends of said arcuate bearing to limit the movement of the handle and the valve plug controlled thereby so that when the handle is turned to one

position the valve will be closed and when turned to the other position the valve will be open. The handle 16 is provided with a shoulder 23 which rests against the shoulder 15 of the plug 10, so that when the handle is turned to one position the shoulder 23 will bear against the shoulder 15 of the plug 10, thereby holding the handle in position.

Fig. 2 shows the device as applied to a vacuum feed system. The tank 1 is connected to the carburetor 25 through the valve 5, the tank 1 having an outlet 2 formed therein at the bottom thereof, and preferably threaded, as shown, to receive the threaded end 6 of the valve body. A pair of parallel ducts or bores 7 and 8 are formed in the valve body and extend from one end to the other thereof, there being a tapered transverse bore 9 communicating with said parallel bores 7 and 8.

Fig. 3 is a sectional view taken substantially on the line 3-3 of Fig. 4. The tank 1 is connected to the carburetor 25 through the valve 5, the tank 1 having an outlet 2 formed therein at the bottom thereof, and preferably threaded, as shown, to receive the threaded end 6 of the valve body. A pair of parallel ducts or bores 7 and 8 are formed in the valve body and extend from one end to the other thereof, there being a tapered transverse bore 9 communicating with said parallel bores 7 and 8.

limit of movement liquid will be free to flow through one of the ducts from the interior of the tank, while the other of the ducts will be closed and at the other limit of movement 5 of the handle the reverse will be the case.

The lower end of the valve body is internally threaded so as to receive a pipe 24 or the like, in free communication with both the ducts 7 and 8. If desired, the outlet 10 from the casing may be at the side or the pipe 24 bent so that the discharge is at an angle to the ducts 7 and 8. One of the ducts, as for instance the duct 8, has an extension 15 30 arranged thereon and projecting beyond the end of the other duct 7 so that, as shown in Fig. 1, and assuming that the duct 7 is closed and the duct 8 open, the gasoline in the tank 1 will be withdrawn through the duct 8 until it reaches the predetermined 20 level 4, dependent upon the length of the extension 30, whereupon the feed through said duct 8 will cease. This indicates to the operator that the reserve supply has been reached and he, being warned, turns 25 the lever 16 to open the other duct 7 by placing it in alignment with the duct 11, so that the reserve quantity of gasoline may flow through the ducts 7 and 11 to the carburetor, and enabling him to reach a point 30 where additional fuel may be purchased or secured.

When it is desired to use the valve in connection with a vacuum feed system, as shown in Fig. 2, the valve is placed in the threaded outlet 2' at the top of the tank and there are a pair of tubes 31 and 32 extending from the bores 7 and 8 into the liquid, one of said tubes, as for instance the tube 32, being longer than the other and extending substantially to the bottom of the tank, so that the liquid 3 in the tank will normally be fed through the tube 31 until it reaches the level 41, whereupon the handle 16 of the valve is turned to open the duct communicating with the tube 32 so that the remaining reserve supply of gasoline in the tank may be withdrawn. In Fig. 7 we have shown how the parts may be provided with characters to denote the portion of the valve.

50 It will be noted that any predetermined proportion of gasoline may be considered as a reserve supply, this reserve supply being the difference between the quantities corresponding to the differences in level at the 55 ends of the inlets to the two ducts. The connection with the tank and pipe line may

be varied, as required, depending upon the particular installation.

Having thus described our invention, it is obvious that various immaterial modifications may be made in the same without departing from the spirit of our invention; hence we do not wish to be understood as limiting ourselves to the exact form, construction, arrangement and combination of parts herein shown and described or uses mentioned.

What we claim as new and desire to secure by Letters Patent is:

In combination with a liquid supply tank, 70 a reserve valve comprising a body member adapted to be arranged at an opening in the top or bottom of said tank, said body member having a pair of ducts entirely therethrough from end to end, extensions insertable into said ducts adapted to conduct the liquid from said tank at different levels, a tapered bore extending laterally through said valve body and communicating with both of said ducts intermediate their ends; 75 a tapered plug seated in said bore and having a pair of ducts independent of each other and extending entirely therethrough from one side to the other, said last-mentioned ducts having their axes arranged in mutually transverse directions and adapted to alternately register and align with the ducts through said body member, a handle for operating said plug and bearing against the body member to prevent axial movement of 80 the plug in one direction, means for retaining said plug and handle in place, and means for limiting the rotational movement of said plug and comprising abutments on said body adapted to be engaged by said handle, 85 whereby the liquid from said tank will normally flow through one of said ducts until it reaches a predetermined level in the tank so that the plug may be actuated to place the other duct into registry with the duct 100 through the plug and permit the remaining reserve supply of liquid to flow therethrough.

In testimony whereof we have hereunto signed our names in the presence of two subscribing witnesses.

EDWARD J. STALDER.
EDWARD SCHOLZ.
